UNITED STATES PATENT OFFICE

THOMAS McGARIGAL, OF BRUCETON, TENNESSEE

LOCOMOTIVE-SAND-PIPE CLEANER

Application filed July 20, 1929. Serial No. 379,827.

This invention relates to a cleaner for the sand pipes of locomotives, and has for one of its objects to provide a novel device of this character through the medium of which air under pressure may be utilized for the purpose of cleaning a sand pipe when the sand becomes clogged therein during damp or rainy weather.

The invention has for a further object to provide a device of the character stated through the medium of which air from the main air reservoir of the locomotive may be utilized for the purpose of cleaning the sand pipe and which shall be equipped with a control valve arranged within the cab of the locomotive so as to be within convenient reach of the engineer.

The invention has for a further object to provide a device of the character stated which shall be adapted to be installed in the sand pipe at a point between the ends of the latter and which when in operation shall create a suction or vacuum in the upper portion of the sand pipe and maintain a blowing action in the lower portion of the pipe.

The invention has for a still further object to provide a device of the character stated which shall comprise but few parts, which may be readily and cheaply manufactured and which may be installed in a sand pipe in a short time and with little labor.

The invention consists in the construction, combination and arrangement of parts hereinafter fully described and claimed and illustrated in the accompanying drawing, wherein:

Figure 1 is an elevational view illustrating the application of the cleaner to a sand pipe of a locomotive; and

Figure 2 is a sectional view taken on a plane extending vertically and centrally through the cleaner.

Referring in detail to the drawing, 1 designates one of the drive wheels, 2 the cab, 3 the sand box, 4 one of the sand pipes, 5 the main air reservoir, and 6 the air control or distributing valve of a locomotive.

The cleaner, which is arranged in the sand pipe 4 above the drive wheel 1 comprises a body or casing 7 which is of substantially

globular formation and connected to the upper and lower portions 4^a and 4^b, respectively, of the sand pipe. A tube 8 extends axially through the body 7 and communicates with the upper and lower portions of the sand pipe 4.

The body 7 is provided with upper and lower coupling extensions 9 and 10, respectively, which are internally screw threaded. The coupling extensions 9 and 10 are of angular formation externally to provide wrench engaging faces 11. The body 7 is provided at its upper side with an inner annular shoulder 12, and it is provided in its lateral side centrally between its upper and lower sides with an air inlet 13. The coupling extension 9 may be directly engaged with the lower end of the upper sand pipe section 4^a or connected thereto by a nipple, not shown.

The tube 8 is of sectional formation. The upper section 8^a of the tube 8 is provided at its upper end with an outer annular flange 14 which rests upon the shoulder 12 to support the tube section within the body 7. The flange 14 is maintained in engagement with the shoulder 12 by the lower end of the upper sand pipe portion 4^a or by the nipple when the latter is used to connect the body 7 to this sand pipe portion. The tube section 8^a communicates with the lower end of the upper sand pipe portion 4^a, and it extends into the body 7 to a point below the air inlet 13. The lower section 8^b of the tube 8 is externally screw threaded for engagement with the coupling section 10, and it extends from a point close to the lower end of the tube section 8^a to the upper end of the lower sand pipe portion 4^b. The tube section 8^b is engaged in the upper end of the lower sand pipe portion 4^b, and it is provided with a wrench engaging rib 15.

A pipe 16 of small diameter extends from the compressed air control or distributing valve 6 to the air inlet 13, and it is provided with a control valve 17 located close to the valve 6 so as to be within convenient reach of the engineer.

The tube 8 provides a sand passage through the body 7, and the body provides an air chamber 18 surrounding the sand passage.

The port 13 provides an air inlet for the air chamber 18, and the annular space 19 between the adjacent ends of the tube sections 8^a and 8^b provides a port which establishes communication between the air chamber and the sand passage. The inner wall of the upper end of the tube section 8^b is flared to provide a constricted outlet 20 for the air intake port 19 of the tube 8. The throat 20 at its larger end is diametrically greater than the tube section 8^a, and it is constricted in a downward direction.

In practice, when the sand pipe 4 becomes stopped up as the result of the clogging of the sand therein during damp or rainy weather, the valve 17 is opened to admit air under pressure to the chamber 18. The air flows from the chamber 18 into the lower tube section 8^b by way of the port 19, and it flows downwardly through this tube section and through the lower sand pipe portion 4^b, with the result that a vacuum or suction effect is produced in the upper portions of the sand pipe and sand passage, and a blowing effect is produced in the lower portions of the sand passage and sand pipe. It has been demonstrated as the result of the use of the cleaner on a locomotive that these vacuum and blowing effects clear the sand pipe of all stoppage in a comparatively short time, and that by the use of the cleaner at intervals the full flowing of the sand through the sand pipe will be insured.

While I have described the principle of the invention together with the structure which I now consider the preferred embodiment thereof, it is to be understood that the structure shown is merely illustrative and that such changes may be made, when desired, as fall within the scope of the invention as claimed.

I claim:

1. A sand pipe cleaner comprising, in combination with a sand pipe of a locomotive, means arranged in the sand pipe below the upper end thereof and adapted to direct air under pressure downwardly and axially through the lower portion of the sand pipe, and means located in the sand pipe above said first means and cooperating therewith to utilize the air passing through said portion of the sand pipe to create a suction in the upper portion of the sand pipe.

2. A sand pipe cleaner comprising, in combination with a sand pipe and a source of air under pressure, a tube arranged in the sand pipe and provided between its ends with an annular inlet port, a casing surrounding the tube and providing a chamber with which said port communicates, a pipe extending from said source to the casing, and a valve in the pipe.

3. A sand pipe cleaner comprising, in combination with a sand pipe and a source of air under pressure, a tube arranged in the

sand pipe and provided between its ends with an annular inlet port having a constricted throat, a casing surrounding the tube and providing an air chamber with which said port communicates, a pipe extending from said source to the casing, and a valve in said pipe.

4. A sand pipe cleaner comprising a casing of substantially globular formation and provided with an air inlet port, and a sectional tube extending diametrically through the casing, the adjacent ends of the tube sections being relatively spaced to provide a port establishing communication between the same and the casing.

5. A sand pipe cleaner comprising a casing provided with an inlet port, a sectional tube extending through the casing, the adjacent ends of the tube sections being relatively spaced to provide a port communicating with the casing and the end of one tube section being flared internally.

6. A sand pipe cleaner comprising a casing of substantially globular formation and provided with diametrically opposed openings, the casing being provided between said openings with an inlet port and at one of said openings with an annular shoulder, a tube section extending into the casing through said last opening, and provided with an annular flange contacting with said shoulder, a sectional tube extending into the casing through the other of said openings and having its inner end spaced from the inner end of said first tube.

7. A sand pipe cleaner comprising a casing having a sand passage extending therethrough and an air chamber surrounding said passage, the casing being provided with an air inlet port for said chamber, and said passage being provided between its ends with an annular inlet port communicating with said chamber.

8. A sand pipe cleaner comprising a casing having a sand passage extending therethrough and an air chamber surrounding said passage, the casing being provided with an air inlet port for said chamber, and said passage being provided between its ends with an air inlet port communicating with said chamber and having a downwardly constricted throat.

9. A sand pipe cleaner comprising a casing having a sand passage extending therethrough and an air chamber surrounding said passage, the casing being provided with an air inlet port for said chamber, and said passage being provided between its ends with an annular air inlet port communicating with said chamber and having a downwardly constricted throat.

10. A sand pipe cleaner comprising a casing having a sand passage extending therethrough and an air chamber surrounding said passage, the casing being provided with an

air inlet port for said chamber, said passage being provided between its ends with an annular inlet port communicating with said chamber and having a downwardly constricted throat, and the diameter of the throat at its widest end being greater than the internal diameter of the passage above the throat.

11. A sand pipe cleaner comprising a tube extending axially through a portion of the sand pipe and provided between its ends with an annular inlet port having a downwardly constricted throat, and means adapted to permit air under pressure to be supplied to the port.

In testimony whereof I hereunto affix my signature.

THOMAS McGARIGAL.
